ATTORNEY.

UNITED STATES PATENT OFFICE.

HERBERT M. DAVIS, OF BROOKLYN, NEW YORK.

WATER MOTOR.

Application filed July 1, 1922. Serial No. 572,234.

To all whom it may concern:

Be it known that I, HERBERT M. DAVIS, a citizen of the United States, residing at the city of New York, borough of Brooklyn, in the county of Kings and State of New York, have invented certain new and useful Improvements in Water Motors, of which the following is a specification.

This invention relates to water power devices whereby the tremendous power carried or possessed by the movement of streams or bodies of water may be utilized to great advantage.

It being well understood that the surf water along the seacoast as it flows toward the shore has considerable power, one of the objects of this invention is to provide mechanism of a nature adapted to utilize a large percentage of such power and convert it to useful purposes.

More specifically stated I have as one object of my invention to so mount a power element as to be rotated in a predetermined direction by the force of the surf water as it flows or rolls toward the shore, such force being exerted practically continuously and irrespective of the rise and fall of the tide and without material interference with the undertow or reverse flow of the water.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which—

Figure 1 is a plan view indicating a preferred embodiment of my mechanism.

Fig. 2 is a vertical section of the same on the line 2—2.

Fig. 3 is a vertical section on the line 3—3 of Fig. 2.

Fig. 4 is an enlarged side view of one of the power units.

Fig. 5 is an end view of the same mechanism.

Fig. 6 is a bottom plan view of one of the floats and the hanger for the shaft.

In carrying out my idea in a practical form I build or erect in any suitable manner a pair of parallel abutments or but-

resses 10, the same extending out from the shore line as far as may be required into the ocean. These buttresses are spaced from each other a suitable distance to accommodate the movable parts between them, and except as now to be stated they are free from each other. I do not wish to be limited in any manner as to the size, design, materials, or spacing of these members, it being understood merely that they are of a suitable size and construction and of rigid stationary nature.

Arranged between the buttresses and preferably mid-way thereof is a rotary power device comprising any desired number of connected units, the length of each unit as well as the number thereof being subject to a mere matter of selection in any installation. As shown especially in Figs. 4 and 5 each unit comprises a shaft 11 upon which are fixed in any suitable manner a series of blades 12, whereby the unit may be regarded as constituting a propeller. As shown each propeller comprises six pairs of blades, each pair being made from a single piece of material such as heavy sheet metal, the blades of each pair projecting in opposite directions from the axis of the shaft and having their points or outer edges arranged spirally with respect to said axis and arranged with the inclination at about 50°, more or less, from the plane of the axis. From Fig. 4 it will be noted that each blade or nearly all of each blade lies or projects forward or outward from the plane of the rear edge thereof perpendicular to the axis at the hub portion or point of connection with the axis. From this fact it follows that a current of water approaching the propeller in the direction of the arrows on Fig. 4 parallel to the shaft will strike against both blades of each pair, causing rotation of the shaft as indicated, and the same current continuing in the same direction will act in succession upon all of the blades in the same manner. It will be seen also that since the spiral periphery of each blade lies approximately in the same continuous spiral as the corresponding periphery of the next adjacent blade the highest degree of efficiency is received. If the direction of the flow of the propelling medium is at an angle to the shaft it will strike almost squarely against one blade of each pair while it will strike against the edge of

105
110

the opposite blade of the same pair. Thus the force will be exerted with high efficiency irrespective of the direction in which the medium may be moving. Any suitable means 5 may be provided to lock the several blades upon the shaft 11 in proper relation to one another.

Referring again to Figs. 1 and 2 I show at 13 a strong beam such as a metal I-beam 10 extending across between the outer ends of the buttresses 10, and in this beam is secured a bearing socket 14 for the connection at a fixed point of the outermost end of the shaft 11^a. This connection is indicated as being 15 in the nature of a ball and socket, thereby permitting the shaft 11^a to oscillate up and down and yet be free to rotate. This beam 13 may be fixed at any desired elevation at or about mean tide level or at an elevation 20 such as will insure that the propellers will be held at a substantially uniform distance beneath the surface of the water so that they will be subjected to the force of the waves and yet be located practically above 25 the undertow or reverse current.

It being remembered that the shaft members may be of considerable length and that the entire apparatus may extend far out into the ocean, it is necessary for the joints 30 between the adjacent shaft members to be suitably supported to keep the propellers at the desired elevation. Consequently I provide one or more floats 15 of any suitable 35 buoyant construction, the same being held from lateral movement in any direction by means of stanchions or guides such as vertical angle members secured to the opposed inner sides of the buttresses. The floats being made of wood or other buoyant material, 40 it is advisable for each float where it has sliding contact with an angle guide member 16, to be faced with a metal angle member 17, the lower end of which is preferably extended as a bracket 18 beneath the float. 45 The several brackets 18 constitute a hanger for a bearing 19 in which is fitted a ball 20 in which the adjacent end of the shaft 11 is journaled and is free to slide endwise to compensate for the movement of the float 50 up or down its guide ways. As indicated in Fig. 2 the ball 14 being held at a fixed point, if the hanger for the inner end of the shaft 11^a moves downward toward the level the shaft will necessarily be obliged to move 55 endwise relatively through the ball.

The next shaft section 11^b is connected to the first section by means of a universal joint 21 of any suitable construction so that one section will rotate with the other irrespective of any possible variation in angle 60 between their axes. The hanger over the inner end of the second shaft section 11^b is the same as already described and therefore permits the endwise movement of this shaft 65 11^b to compensate for the angular movement

between the axes of the second shaft section and the third section 11^c as well as for the straightening action already described between the first two sections. Finally the last section of the shaft which may or may not carry propeller blades is journaled in a ball and socket bearing 19'. This last shaft section may slide endwise as a whole through the bearing 19', or a sleeve 22 may be fitted in the bearing and adapted to oscillate therein around the axis of the ball 20' therein and within which sleeve the shaft section 11^c may be free to slide endwise to compensate for the conditions above described. Any suitable member such as a 80 wheel 23 may be fixed to the end of the sleeve or the last shaft section for the delivery of the power incident to the rotation of the shaft. This member may be housed within a power house where the power may 85 be converted and from which it may be transmitted as may be found desirable at any particular installation.

I claim:

1. In a water motor, the combination of a 90 shaft, a series of propeller blades mounted thereon, the blades being arranged in pairs extending diametrically opposite each other from the shaft and with their points projecting and lying practically all in advance 95 of a plane perpendicular to the shaft at the point of connection between the hub thereof and the shaft, the peripheries of the blades being spirally arranged and with the periphery of one blade forming a substantial continuation of the spiral of the periphery of the blade of the next adjacent pair, and means to fix the blades from rotation on the shaft.

2. In a water motor, the combination of a 105 plurality of shaft members, propeller means on each shaft member, stationary means to journal the remote ends of the shaft members for rotation at fixed points, means to sustain the intermediate joints between 110 pairs of adjacent shaft members for universal movement irrespective of the variable angles between the axes of the adjacent shaft members, said suspending means comprising floats, and means for holding the 115 floats from movement in any direction except vertically.

3. In a water motor, the combination of a 120 plurality of shaft sections, universal joint connections between adjacent sections, propeller means on the several sections, a float for each universal joint connection, means to hold the float from lateral movement in any direction, a hanger extending beneath each float for supporting the joint, and a ball and socket bearing for the adjacent shaft providing for endwise movement of the shaft as well as its rotation.

4. In a device of the class set forth, the 125 combination of a pair of rigid supports ex- 130

tending into the sea, a rigid beam extending between them, a shaft having fixed ball and socket bearing in said beam, a stationary power inclosure for the remote end of the
5 shaft, propeller means on the shaft for rotation thereof, and means for journaling the latter mentioned end of the shaft in said

inclosure, said journaling means comprising a sleeve journaled for rotation and into which the adjacent end of the shaft is slid- 10 ably fitted.

In testimony whereof I affix my signature.

HERBERT M. DAVIS.
